ILLINOIS, ASSIGNEES TO WESTERN ELECTRIC COMPANY, INCORPORATED, OF NEW
YORK, N. Y., A CORPORATION OF NEW YORK.

MACHINE FOR COATING CORES.

Application filed March 29, 1922. Serial No. 547,924.

- This invention relates to a machine for coating cores in strand form, and more particularly to a machine which utilizes pulp as a coating material.
- 5 The invention has as its primary object the production of a machine for coating a core with pulp in such manner that the pulp conforms with and is attached to the core without the use of any adhesive substance.
- 10 The apparatus shown in the drawing is an embodiment of the invention adapted for coating a core in strand form with pulp, and may be used to advantage in the insulating of electrical conductors. The invention is not, however, limited to a machine of the type shown nor is the embodiment illustrated limited to the coating of metallic strands, but the strands may be made of any material upon which it is desirable to form a pulp coating, and it is to be understood that the invention is only to be limited by the scope of the appended claims. The term "core in strand form" as used in the specification and appended claims, refers
- 15 to a core having the configuration resembling a fibre, hair, filament, string, small cord, or the like, or in the nature of a rope consisting of fibres, yarns or wires twisted together.
- 20 More specifically, an embodiment of the invention comprises a mechanism for bringing the core to be coated into intimate contact with a liquid containing pulp whereby pulp is applied thereto, removing the core from the pulp mixture to permit the deposited pulp to cling to the core; a mechanism for removing the greater portion of liquid from the pulp on the core; a mechanism for forming the pulp so that it conforms with the shape of the core; and a mechanism for removing substantially all of the moisture from the pulp so that a dry pulp coating remains on the core.
- 25 In the apparatus shown in the drawings a preferred form of mechanism for applying pulp to the core comprises a receptacle containing the pulp mixture and a hollow drum rotatably mounted therein, the drum having a foraminous portion which supports the core. The level of the pulp mixture within the drum is maintained lower than the level of the mixture in the receptacle so that a
- 55 circulation of pulp mixture is maintained into the drum through the foraminous portion, which causes the pulp to be strained onto the foraminous portion and applied to the core supported thereon. The core with the pulp deposited thereon is withdrawn from the top of the drum and suspended in such a manner that the pulp deposit is caused to cling to the core due to gravity 60 the surface tension of the liquid in the pulp mixture, and the felting action of the pulp fibers. In place of the mechanism just described for applying pulp to the core the "wet end" of a Fourdrinier machine may be employed or this operation may be performed by passing the core beneath the discharged opening of a pipe feeding the pulp mixture. Any other suitable means may be employed for applying the pulp to the core 65 without departing from the spirit and scope of the present invention.
- 70 A successful form of mechanism for removing the greater portion of the liquid from the pulp on the core consists of a plurality of squeezing rolls between which the core with the pulp clinging thereto is passed. It has been found desirable to provide a single auxiliary roll of foraminous material 75 over which the core is passed in advance of its subjection to the squeezing rolls in order that the "free liquid," so to speak, in the pulp mixture is drained off in a manner which will not cause the pulp coating to be 80 washed off of the core. This auxiliary roll, however, may be dispensed with if other means is provided for removing the "free liquid" which may in fact be removed by permitting it to drain off by gravity. The 85 squeezing rolls referred to above not only remove the greater portion of the liquid from the pulp on the core, but also form the pulp into a ribbon extending at opposite 90 sides of the core.
- 95 The mechanism for forming the pulp around the core and causing it to conform to the shape thereof comprises a pair of spring pressed plates which engage the core longitudinally and at opposite sides thereof, the plates being rotated around the core. These plates in rotating wrap the edges of the ribbon, formed by the squeezing rolls, around each other and around the core so that the

pulp conforms to the shape of the core. This former also causes a thorough intermingling of the fibers of the pulp and fastens it securely to the core. It is to be understood, however, that the invention is not limited to the construction of former above described and shown in the drawings, but also contemplates any apparatus for performing this operation limited in structure 10 only as defined in the appended claims.

The mechanism for removing substantially all of the moisture from the pulp coating comprises drums over which the core with the pulp coating thereon is passed, the drums being heated with steam or by any other suitable means. Other means, however, may be employed for drying out the pulp coating without departing from the spirit and scope of the invention.

When desired the pulp coating may be marked either for decorative purposes or, in the case of electrical conductors, for identification and to distinguish them from each other. One form of marking means may 20 comprise a strand wrapping around the pulp coating, the wrapping when desired having a color different from that of the coating.

The word "pulp" as used in the specification and claims is to be understood as defining and including any cohering fibrous mass whether suspended in a liquid, moist, or substantially dry.

In the accompanying drawings—

Fig. 1 is a side elevation of an apparatus embodying the invention;

Fig. 2 is an enlarged top plan view of the apparatus shown in Fig. 1, parts being omitted for the sake of clearness;

Fig. 3 is an enlarged detail view in side elevation of the forming device;

Fig. 4 is an enlarged vertical sectional view taken on the lines 4—4 of Fig. 3;

Fig. 5 is an enlarged, fragmentary sectional view of the drum for conveying the core into contact with the liquid containing pulp;

Fig. 6 is an enlarged, fragmentary sectional view of the auxiliary roll for removing "free liquid" from the pulp deposited on the core;

Figs. 7, 8, 9 and 10 are enlarged views showing the form of the pulp coating on the core as it is delivered from the liquid containing pulp, the squeezing rolls, and former respectively;

Fig. 11 is a top plan view of the core and pulp coating shown in Fig. 8, and

Fig. 12 is a fragmentary side elevation disclosing an alternative apparatus for applying pulp to the core and causing it to cling thereto.

Referring now to the drawings in detail, in which like reference numerals designate similar parts throughout the several views, the core to be coated is fed from a supply

20, over an idler roll 21, and thence around a drum 22 which is partly submerged in a liquid containing pulp within a semi-spherical trough 23. The drum 22 comprises a pair of sheet metal sides 24, Fig. 5, and a peripheral portion 25 secured thereto. The portion 25 is provided with a plurality of relatively large perforations 26 which are covered with a narrow strip of fine wire mesh 27. The core in passing around the drum lies 75 upon the wire mesh 27 as is shown in Fig. 2. The drum 22 has a centrally disposed tubular axle 28 which is rotatably mounted in suitable bearings 29 carried by a framework 30 which supports all the elements of 80 the apparatus.

In order to apply pulp to the core as it passes over the drum 22 the pulp mixture within the drum is maintained at a lower level than that of the level of the pulp mixture in the tank 23, as indicated by dotted lines A and B respectively. This difference in levels is maintained by a siphon pipe 31 which has its inlet opening submerged in the pulp mixture within the drum 22 and its discharge through the tubular axle 28. A continuous circulation of the pulp mixture is maintained in the tank 23 by feeding the pulp mixture from a supply tank 32 into the tank 23 and out of the said tank through 90 a pipe 19 into a receiving tank (not shown) from which it is pumped back into the supply tank 32 in any suitable manner. As the drum 22 carries the core thereon through the tank due to the difference in the levels of the liquid within the drum and the tank 23, the liquid in the tank 23 will pass through the wire mesh 27 and perforations 26, straining the pulp onto the outer surface of the wire mesh, and applying pulp to the core supported thereon. In order to keep the wire mesh clean prior to its reception of the core and a new coating of pulp, it is washed by a jet of water under pressure which is supplied through a nozzle 33.

The drum 22 is rotated in the direction indicated by the arrow. The core with a coating of pulp thereon leaves the drum at the top thereof, and the force of gravity, surface tension of the liquid in the pulp mixture, and the felting action of the pulp fibers cause it to surround the core and cling to it in substantially the form shown in Fig. 7.

From the drum 22 the core with a pulp coating thereon is passed over an auxiliary roll 34 and then between a pair of squeezing rolls 35 and 36. These rolls are rotatably mounted between a pair of brackets 37 secured to an upright standard 38 supported by the framework 30. The shaft carrying the roll 36 is driven through a pulley attached thereto which is actuated by a motor 39 in any suitable manner as by means of the belts 40 and 41 shown. The rolls 35 and 120

36 preferably draw the core from the supply roll 20, over the drum 22, causing it to rotate, and then between them.

The auxiliary roll 34, as shown in Fig. 6, 5 is a hollow sheet metal drum having a peripheral slot covered with a strip of fine wire mesh 42. It has been found preferable to employ the auxiliary roll 34 and to make it foraminous where it engages the core and 10 pulp coating thereon in order that the "free liquid," so to speak, may be strained off away from the core and coating without causing a back flow of the liquid which would tend to wash off the pulp coating 15 which at this stage is very soft and moist and easily removed from the core. With the "free liquid" removed the coating has greater strength due to a closer felting of the fibers so that when the core and coating are passed 20 through the squeezing rolls the coating will not be torn from the core.

The squeezing rolls may be formed of 25 rubber and forced together by any suitable tension means which is adjustable to present the proper pressure on the core and pulp coating as they pass between the rolls. These 30 rolls remove the greater portion of the liquid from the pulp mixture and form the pulp into a thin ribbon which extends laterally from each side of the core as is shown in 35 Figs. 8 and 11. This squeezing operation also tends to mat or felt the fibers into more intimate relation, increase the tensile strength of the covering and secure it to the core.

From the squeezing rolls the core with its 40 ribbon pulp coating is drawn through a former which wraps the projecting edges of the ribbon around the core and around each 45 other, the appearance of the coating after it is first acted on by the former and after the forming action is completed being shown clearly in Figs. 9 and 10. The former causes a thorough intermingling of the pulp fibers 50 and shapes the coating so that it embraces the core and conforms to the shape thereof and moulds the coating into a mass so homogeneous that upon cutting the core and coating the latter will not fray or ravel 55 and will not become easily detached from the core.

The former, shown in detail in Figs. 3 and 4, comprises two cup shaped collars 43 and 44 held together and in spaced relation by 55 means of rods 45. Integral with said collars 43 and 44 is a sleeve 46 and 46' respectively which are rotatably mounted within suitable bearings in the standards 38 and another pair of standards 47 supported by 60 the framework 30. Two plates 48 and 49 have projecting tongues which are bent around two of the rods 45 to pivotally support the plates in opposed relation to each other. Compression springs 50 engage the 65 rear faces of each of the plates 48 and 49

and tend to force them together. The springs 50 are put under the requisite compression by means of adjusting screws 51 which are mounted in brackets 52 secured to the rods 45. The ends of the plates 49 and 48 adjacent the squeezing rolls 35 and 36 are flared outwardly so as to present a smooth surface to the core and pulp coating as they pass from the said rolls through the sleeve 46 and between the forming plates 48 and 49. The core passes from the forming plates through the sleeve 46.

The plates 48 and 49 are rapidly rotated around the core and the pulp coating thereon through the medium of a pulley 18 secured to the sleeve 46' the pulley being 80 driven by the motor 39 through a belt 17.

The forming plates 48 and 49 wrap the projecting edges of the pulp ribbon about each other and around the core in much the 85 same manner as though the core and pulp ribbon were rolled on a table top with the palm of the hand.

The core with its formed coating is drawn 90 from the former and subjected to a mechanism for thoroughly drying out the coating. The means shown for performing this operation are a pair of wide hollow drums 52 and 53 heated internally and having a plurality of grooves 53' formed thereon, Fig. 2, 95 which receive the core, guides (not shown) being provided for directing the core over first one drum and then the other until it has traversed all of the grooves on both drums, after which it is stored on a receiving drum 54. The drums 52 and 53 are 100 revolvably mounted in suitable bearings carried by vertical standards supported by the framework. The receiving drum 54 is also revolvably mounted in bearings carried by 105 brackets 55 supported by the framework 30 and is driven by the motor 39 through suitable belting, the drums 52 and 53 being driven from the drum 54 also through a suitable belting system.

Although it has been stated that the primary object of the invention is to apply a coating of pulp to a core without the use of any adhesive substance, the machine herein disclosed may be used with a pulp mixture 115 containing a sizing substance, or the pulp may be deposited on a core which has been previously treated with an adhesive agent, without departing from the spirit and scope of the present invention.

When desired the pulp coating may be marked either for decorative purposes, or in the case of electrical conductors, for identification and to distinguish them from each other. One form of marking means may 120 comprise a strand server 55' of any well-known construction. The server 55' spirally wraps a strand around the pulp coating in a manner well known to those skilled in the art. Preferably the strand is served onto 125 130

the coating while the latter is still moist to a slight degree, so that it is embedded to some extent in the pulp coating. This strand also serves to strengthen the pulp coating and hold it in place on the core, although it is to be clearly understood that such strand wrapping is not necessary to produce an entirely commercial pulp coating in accordance with the process herein disclosed.

10 An alternative form of apparatus for applying pulp to the core and permitting it to cling thereto is illustrated in Fig. 12, in which a supply tank 60 containing the pulp mixture is provided. This tank has in communication therewith a pipe 61 terminating at its discharge end in a nozzle 62. The strand to be coated is fed below the nozzle 62 by any suitable means (not shown), the nozzle continuously discharging pulp mixture on top of the core. After the core passes from beneath the nozzle it is suspended so that the pulp coating thereon is caused to cling to it. The excess pulp mixture discharged by the nozzle is caught in a pan 63 and pumped back into the supply tank 60 by any suitable means (not shown).

Although the foregoing description deals with the coating of one core, it is clear as shown in Fig. 2 that the mechanism is equally applicable to coating a plurality of cores simultaneously with pulp and individually treating the pulp on the cores to constitute a coating therefor.

What is claimed is:

35 1. In a machine for coating a core in strand form with pulp, a receptacle holding a supply of liquid containing pulp, means for causing relative movement between the core and said liquid whereby pulp is applied to the core, means for removing liquid from the pulp coating, and means for forming said pulp so that it constitutes a coating conforming with the core.

45 2. In a machine for coating a core in strand form with pulp, a receptacle holding a supply of liquid containing pulp, means for causing relative movement between the core and liquid whereby pulp is applied to the core to form a coating, means for removing a portion of the liquid from the pulp on the core, means for forming said pulp so that it constitutes a coating conforming with the core, and means for removing the remaining moisture from the coating.

55 3. In a machine for coating a core in strand form with pulp, a receptacle holding a supply of liquid containing pulp, a foraminous carrier associated with said receptacle, means for causing relative movement between said core and the liquid whereby pulp is strained through said foraminous carrier onto the said core to constitute a coating, and means for forming said coating so that it has a curved outer surface.

65 4. In a machine for coating a core in

strand form with pulp, means for subjecting the core to a wet pulp whereby pulp is deposited thereon, means for squeezing the deposited pulp to remove excess moisture, and means for exerting pressure on the deposited pulp and core to form the pulp into a coating conforming with the core and retained on the core by a felting of the pulp fibers.

5. In a machine for coating a core in strand form with pulp, a receptacle holding a supply of liquid containing pulp, means for bringing the core and said liquid into intimate contact and causing a relative movement between the core and pulp whereby pulp is applied to the core, and a former for shaping the pulp so that it conforms with the core, said former comprising a rotating member engaging the pulp coating.

6. In a machine for coating a core in strand form with pulp, a receptacle holding a supply of liquid containing pulp, means for bringing the core and said liquid into intimate contact and causing a relative movement between the core and pulp whereby pulp is applied to the core, a former for shaping the pulp so that it conforms with the core, and means for causing relative lateral movement between the former and said core.

7. In a machine for coating a core in strand form with pulp, a receptacle holding a supply of liquid containing pulp, means for bringing the core and liquid into intimate contact and causing a relative movement between the core and liquid whereby pulp is applied to the core, and a former for shaping the pulp so that it conforms with the core, said former comprising spring pressed rotatable members engaging the pulp coating.

8. In a machine for coating a core in strand form with pulp, a receptacle holding a supply of liquid containing pulp, means for bringing the core and said liquid into intimate contact and causing a relative movement between the core and liquid whereby pulp is applied to the core, a former for shaping the pulp so that it conforms with the core, said former comprising members engaging the pulp at different points on the core, and means for rotating said members.

9. In a machine for coating a core in strand form with pulp, a receptacle holding a supply of liquid containing pulp, means for bringing the core and said liquid into intimate contact and causing a relative movement between the core and pulp whereby pulp is applied to the core, a former for shaping the pulp so that it conforms with the core, said former comprising members engaging the pulp, and means for rotating said members around the core.

10. In a machine for coating a core in

- strand form with pulp, means for attaching a pulp ribbon to the core, and means for forming said ribbon on the core to constitute a coating conforming with the core and retained thereon by a felting of the pulp fibers.
11. In a machine for coating a core in strand form with pulp, means for attaching a pulp ribbon to the core longitudinally thereof, and means for wrapping said ribbon around the core to constitute a coating therefor and conforming with the core and retained thereon by a felting of the pulp fibers.
12. In a machine for coating a core in strand form with pulp, a receptacle holding a supply of pulp, means for causing relative movement between the pulp and the core whereby pulp is applied to the core, means for fabricating the pulp into ribbon form, and means for wrapping said pulp ribbon around the core.
13. In a machine for coating a core in strand form with pulp, a receptacle holding a supply of liquid containing pulp, means for causing relative movement between the liquid and the core whereby pulp is applied to the core, means for squeezing the pulp coating into ribbon form, and means for wrapping the said pulp ribbon around the core.
14. In a machine for coating a core in strand form with pulp, a receptacle containing pulp, means for causing relative movement between the pulp and the core whereby pulp is applied to the core, means for fabricating the pulp into ribbon form, spring pressed members disposed in engagement with said pulp ribbon, and means for causing relative lateral movement between said spring pressed members and the core.
15. In a machine for coating a core in strand form with pulp, a receptacle holding a supply of liquid containing pulp, a liquid removing mechanism, a former for shaping the pulp so that it conforms with the core, and means for drawing the core into contact with the liquid and then through the liquid removing mechanism and former.
16. In a machine for coating a core in strand form with pulp, a receptacle holding a supply of liquid containing pulp, a carrier having a foraminous portion and mounted in contact with said liquid, a squeezing device, a forming device for shaping the pulp so that it conforms with the core, a drying mechanism, and means for submitting said core to said carrier, squeezing device, forming device and said drying mechanism.
17. In a machine for coating a core in strand form, a receptacle holding a supply of liquid containing pulp, means for causing relative movement between the core and the liquid whereby pulp is applied to the core, and means for applying a designation to the deposited pulp.
18. In a machine for coating a core in strand form, a receptacle holding a supply of liquid containing pulp, means for causing relative movement between the core and the liquid whereby pulp is applied to the core, and means for serving a strand wrapping around the pulp on the core.
19. In a machine for coating a core in strand form with pulp, a foraminous carrier for the core, a receptacle holding a supply of liquid containing pulp, means for causing relative movement between the said carrier and the liquid whereby pulp is strained onto the said core, means for forming the said pulp so that it conforms with the core, and means for serving a strand wrapping around the pulp on the core.
20. In a mechanism for coating a core in strand form, in combination a tank containing a mixture of pulp, a drum rotatable therein and provided on its periphery with a foraminous portion designed to support the core to be coated, means for maintaining a difference of pressure between the inside and outside of the drum whereby pulp will be strained onto the core and means for forming the pulp into a coating conforming with the core.
21. In a mechanism for coating a core in strand form, in combination a tank containing a mixture of pulp, a drum rotatable therein and provided with a foraminous portion on its periphery designed to contact with the core to be coated, means for maintaining a lower pressure within the drum to cause a flow from the tank through the foraminous portion of the drum whereby the pulp will be strained onto the core and means for forming the pulp into a coating conforming with the core.
22. In a machine for coating a core in strand form with pulp, a receptacle holding a supply of liquid containing pulp, means for causing relative movement between the core and said liquid whereby a coating of pulp is applied to the core, means for removing "free liquid" from the pulp on the core, and means for forming the coating so that it constitutes a covering for the core conforming therewith.
23. In a machine for coating a core in strand form with pulp, a receptacle holding a supply of liquid containing pulp, means for causing relative movement between the core and the liquid whereby a coating of pulp is applied to the core, a former for working the pulp so that it constitutes a covering for the core conforming therewith, and a traveling member engaging the pulp on the core for removing the "free liquid" therefrom, said member located between the pulp supply and the former and comprising a roller in contact with the pulp on the core.
24. In a machine for coating a core in strand form with pulp, a receptacle holding

- a supply of liquid containing pulp, means for causing relative movement between the core and the liquid whereby pulp is applied to the core, means for fabricating the pulp 5 into a coating surrounding the core, the outer surface of said coating being substantially equi-distant from the core at all points, and means for removing substantially all of the moisture from said coating.
- 10 25. In a machine for coating a core in strand form with pulp, means for attaching a pulp ribbon to the core, and means for fabricating the said ribbon so that it surrounds the core to form a coating, the outer 15 surface of said coating being substantially equi-distant from the core at all points and retained on the core by a felting of the pulp fibers.
- 20 26. In a machine for coating a core in strand form with pulp, means for applying pulp to the core and means for forming the applied pulp to cause a felting of the pulp fibres whereby said coating surrounds the core and is retained thereon by the felting of 25 the pulp fibres.
27. In a machine for coating a core in strand form with pulp, means for applying a pulp coating on the core, and means for serving a strand wrapping around the 30 said coating.
28. In a machine for coating a metallic core in strand form, means for applying unfinished paper free of adhesive material to the core and means for completing the fabrication of the paper on the core to cause a felting of the pulp fibres and to impart thereto a curved outer surface, whereby said paper surrounds the core and is retained thereon by the felting of the pulp fibres.
- 35 40 29. In a machine for coating a metallic core in strand form, means for applying unfinished paper free of adhesive material in a wet state to the core and means for drying and completing the fabrication of the paper on the core to cause a felting of the fibres and impart thereto a curved outer surface.
- 45 30. In a machine for coating a metallic core in strand form, means for applying unfinished paper in ribbon form to the core,
- and means for completing the fabrication of 50 the paper ribbon into a coating for the core conforming substantially with the core.
31. In a machine for coating a plurality of cores in strand form with pulp, a receptacle holding a supply of liquid containing 55 pulp, means for causing relative movement between the cores and said liquid whereby pulp is applied to the cores, means for removing the liquid from the pulp on the cores, and means for individually forming 60 said pulp on each core so that it constitutes a coating conforming therewith.
32. In a machine for coating a plurality of cores in strand form, means for applying unfinished paper free of adhesive material 65 to the cores, and means for individually completing the fabrication of the paper on each core to cause a felting of the fibres of the paper and to constitute a coating surrounding each core.
- 70 33. In a machine for coating a plurality of cores in strand form with pulp, means for attaching pulp to the cores, means for forming said pulp into individual ribbons on each core, and means for individually 75 forming said ribbons so that they constitute a coating surrounding each core and conforming therewith.
34. In a machine for coating a core in strand form, means for applying unfinished 80 paper free of adhesive material to the core, and means for completing the fabrication of the paper on the core to cause a felting of the fibres of the paper and to impart to the coating a curved outer surface.
- 85 35. In a machine for coating a core in strand form, means for applying unfinished paper free of adhesive material in ribbon form to the core, and means for completing the fabrication of the paper ribbon into a 90 coating surrounding the core conforming substantially with the core and retained on the core by a felting of the pulp fibers.

In witness whereof, we hereunto subscribe our names this 25 day of March A. D., 1922.

HOWARD GEORGE WALKER.
ALBERT THOMAS MARCH.
